SHUTTLE CHECK

Carl D. Brown, Hopedale, Mass., assignor to
Draper Corporation, Hopedale, Mass., a cor-
poration of Maine

Application January 6, 1937, Serial No. 119,304

4 Claims. (Cl. 139—185)

The present invention pertains to fly shuttle looms, and has more particular reference to shuttle boxes and shuttle stopping instrumentalities for such looms.

5 Looms of the type to which my invention pertains commonly include a reciprocating lay having a shuttle box, a picker stick and picker moving longitudinally of the shuttle box for picking the shuttle, and means in the shuttle box 10 for frictionally retarding the incoming shuttle. In prior constructions, the final stopping of the incoming shuttle was effected by engagement of the shuttle with the picker, which results in objectionable wear and mutilation of the picker 15 and also in the final stopping position of the shuttle varying with the depth of the hole in the picker and with other variable factors.

The principal object of the present invention is to provide a fly shuttle loom having a lay, 20 shuttle box, shuttle and picker as aforesaid, and novel shuttle stopping means, as defined in the appended claims, for stopping the incoming shuttle independently of the picker.

The aforesaid object of the invention is conveniently accomplished in the construction illustrated on the accompanying drawing, of 25 which:

Fig. 1 is a plan view of a part of a loom having the preferred embodiment of my invention applied thereto;

30 Fig. 2 is a view of the same with the shuttle absent from the shuttle box; and

Fig. 3 is a view of the same in front elevation.

35 The loom shown on the drawing is generally of conventional construction, except as herein-after described in detail, and is accordingly but fragmentarily illustrated. Of the conventional construction, the drawing shows a part of a lay 1 which is mounted on swords as 2 for reciprocation towards and from the front of the loom, the lay being slotted at 3 to permit movement of a picker stick 4 carrying a picker 5 for picking a shuttle 6. The lay has a shuttle box in 40 which the shuttle is received at the end of its flight, and the shuttle box is provided with shuttle checking and stopping devices to be described. It will be understood that a picker, shuttle box and checking devices, not shown, may be provided at the other side of the loom.

45 The shuttle box shown on the drawing includes a front box plate 7 having a shuttle guiding surface 8 and a back box plate 9 having a shuttle guiding surface 10. The inner end of the 50 front box plate is fixed to the lay by a bolt 11

and the inner end of the back box plate is fixed to the sword 2, the shuttle guiding surfaces 8 and 10 being approximately parallel and spaced apart a distance slightly greater than the width of the shuttle. The inner end 12 of the shuttle 5 box is open, as is usual in looms of this type. The outer ends of the box plates are fixed to the lay in a manner to be described, and the outer end of the shuttle box is closed by the picker and the novel shuttle stopping means of 10 the present invention.

The shuttle box is provided with any suitable means for controlling the loom protection mechanism. To this end, there is shown on the drawing a shuttle operated cam member 13 and a lever 14 operated by the cam for controlling a protector rod finger 15. This controlling means is not of the present invention, it being disclosed and claimed in my copending application, Serial Number 118,593, filed December 31, 1936, now 20 Patent 2,084,550 granted June 22, 1937.

The shuttle box is also provided with a suitable shuttle checking means for retarding the incoming shuttle. I prefer to use for this purpose plungers, shown at 16, loosely mounted in the 25 back box plate and yieldingly urged into frictional engagement with the shuttle by a spring 17. In common with other shuttle checking devices, the plungers 16 retard the incoming shuttle but will not stop it.

30 The present invention provides novel means for stopping the incoming shuttle precisely in a predetermined position in the shuttle box independently of the picker. In the embodiment shown on the drawing, the outer end of the front 35 box plate 7 is provided with an integral extension 18 which extends outwardly beyond the shuttle guiding surface 8 to provide a shelf of less height than the remainder of the box plate. A lever 19 is pivotally mounted on the extension 18 in front of the path of the picker 5, by being pivoted intermediate its ends on a bolt 20. The bolt 20 passes down through the lever and the extension and is secured in a flange on the metal lay end 21. This lever extends generally longitudinally of the lay and shuttle box and is provided at its inner end with a shuttle engaging surface 22. The surface 22 is inclined outwardly and rearwardly toward the path of the picker, for engaging the usual pointed end of the shuttle 45 50 adjacent the picker.

The back box plate 9 is provided with an extension 23, pivot bolt 24, and lever 25 having shuttle engaging surface 26 which are similar to the extension, pivot bolt and lever just de-

scribed except that, the lever 25 being on the back side of the path of the picker, the surface 26 is inclined outwardly and forwardly toward the path of the picker. The bolts 20 and 24 5 may be provided with eccentric portions engaging the respective levers, for adjusting the levers forwardly and rearwardly. These bolts also serve as means for fixing the outer ends of the box plates to the lay.

10 The shuttle stopping means of the present invention includes spring means for yieldingly urging the shuttle engaging surfaces 22 and 26 toward each other. I prefer to use for this purpose a single coiled spring which is connected to 15 both levers, the spring 27 shown on the drawing being a compression spring which extends between the outer ends of the levers 19 and 25 and urging said ends away from each other. The ends of the spring may be positioned in pockets in the 20 levers as shown.

I have also provided adjustable stop means for 25 positively limiting the extent to which the levers 19 and 25 may be moved by the spring 27. In the form shown, a lug 28 is formed integrally with the extension 18 at the outer end thereof and projects upwardly in front of the lever 19. A set-screw 29 is threaded into the lug 28 and engages the lever 19 at a point outwardly from the pivot bolt 20. A similar lug 30 and set-screw 30 31 are carried by the extension 23 for cooperation with the lever 25. The set-screws 29 and 31 are separately adjustable to hold the shuttle engaging surfaces 22 and 26 apart to provide a path therebetween for the picker. Such adjusting means may be utilized to vary the final stopping 35 position of the shuttle in the shuttle box as well as to center the surfaces 22 and 26 with respect to the picker.

In the operation of the loom, the shuttle stopping 40 levers above described offer very little resistance to the picking of the shuttle out of the shuttle box. When the shuttle returns to the shuttle box shown from the other side of the loom, it first operates the cam 13 and is therefore retarded by frictional engagement with the plungers 16. The incoming shuttle then strikes the shuttle engaging surfaces of the levers 19 and 25. Such surfaces, being inclined as 45 above described, will center the shuttle with respect to the picker and will then stop the shuttle in a predetermined position in the shuttle box. I prefer that the shuttle be thus stopped before it comes solidly against the picker.

It will be apparent that the shuttle stopping 50 means of the present invention will not permit the stopping position to vary with the depth of the shuttle-receiving hole in the picker, and the variable factors. Furthermore, such means centers the shuttle with respect to the picker and 55 relieves the picker of any shuttle stopping function. I find that the slight yielding of the shuttle checking levers provided by spring means such

as spring 27 is necessary to prevent rebounding of the shuttle.

Having fully disclosed the preferred embodiment of my invention, I claim:

1. In a fly shuttle loom, the combination of a 5 lay having a shuttle box, a shuttle, a picker moving longitudinally of said shuttle box for picking the shuttle, and shuttle stopping means on the lay comprising a pair of levers pivoted to the lay and extending longitudinally of the lay on opposite sides of said picker, each of said levers having a shuttle engaging surface at its inner end, spring means acting on said levers to yieldingly urge the shuttle engaging ends thereof toward each other, and adjustable stop means for positively limiting movement of said levers by said 10 spring means.

2. In a fly shuttle loom, the combination of a 15 lay having a shuttle box, a shuttle, a picker moving longitudinally of said shuttle box for picking the shuttle, and shuttle stopping means on the lay comprising a pair of levers pivoted intermediate their ends and extending longitudinally of the lay on opposite sides of said picker, each of said levers having a shuttle engaging surface at its 20 inner end, a single coiled spring connected to said levers and yieldingly urging the shuttle engaging ends thereof toward each other, and positive stop means engaging said levers and limiting movement of the same by said spring. 25

3. In a fly shuttle loom, the combination of a 30 lay having a shuttle box, a shuttle, a picker moving longitudinally of said shuttle box for picking the shuttle, and shuttle stopping means carried by said shuttle box at the outer end thereof, said means comprising a pair of levers pivoted intermediate their ends and extending longitudinally of the lay on opposite sides of said picker, each of said levers having a shuttle engaging surface at its 35 inner end, a coiled compression spring extending between the outer ends of said levers and yieldingly pushing said ends apart to thereby urge said shuttle engaging surfaces toward each other, and adjustable stop means for positively limiting movement of said levers by said spring. 40

4. In a fly shuttle loom, the combination of a 45 lay having a shuttle box, a shuttle having pointed ends, a picker moving longitudinally of said shuttle box for picking the shuttle, and shuttle stopping means carried by said shuttle box at the outer end thereof, said means comprising a pair of levers pivoted intermediate their ends on opposite sides of said picker, each of said levers having at its inner end a shuttle engaging surface which is inclined outwardly and toward the path 50 of said picker for engaging the end of the shuttle adjacent the picker, a single spring engaging both of said levers and yieldingly urging the shuttle engaging ends thereof toward each other, and separate adjustable stop means for each of 55 said levers. 60

CARL D. BROWN.
